[57] CLAIM

The ornamental design for a tea kettle, as shown and
described.

DESCRIPTION

FIG. 1 is a top front perspective view of a tea kettle
showing my new design;
FIG. 2 is a left side elevational view thereof;
FIG. 3 is a top plan view thereof;
FIG. 4 is a front elevational view thereof;
FIG. 5 is a rear elevational view thereof; and
FIG. 6 is a fragmentary sectional view thereof on a
enlarged scale taken on line 6—6 of FIG. 2, the handle
having been omitted for convenience of illustration.
The bottom of the design is flat.
